BEDSIDE MONITOR

Michael L. Sokol, Littleton, Mass., assignor to
American Optical Corporation, Southbridge, Mass.

Filed May 6, 1974, Ser. No. 467,438

Term of patent 14 years

Int. Cl. D24—01
U.S. Cl. D83—1 F

FIG. 1

FIG. 2

FIG 3

FIG 4

FIG. 1 is a front perspective view of a bedside monitor, embodying my new design;

FIG. 2 is a rear perspective view taken from below the horizontal plane;

FIG. 3 is a top plan view thereof; and

FIG. 4 is an elevational view of the right side of a bedside monitor embodying my new design, the left side being of substantially the same appearance.

I claim:

The ornamental design for a bedside monitor, as shown and described.
